Primary Examiner — Cynthia Ramirez(74) *Attorney, Agent, or Firm* — D L Tschida(57) **CLAIM**

The ornamental design for a molded wheel, as shown and described.

DESCRIPTION

FIG. 1 is a perspective drawing showing a front and side views of my new design for a molded wheel.

FIG. 2 is a front view thereof;

FIG. 3 is a rear view thereof;

FIG. 4 is a cross section view taken from FIG. 3 along section lines 4-4;

FIG. 5 is a side view thereof, wherein the other side is a mirror image and wherein a spacer bushing fitted to the hub is shown in dashed line and comprises no part of the invention; and, FIG. 6 is a perspective drawing showing an enlarged partial section of the wheel and wherein partial rear and side views are shown thereof.
